N. A. PATTERSON.
GRAIN AND GRASS HARVESTER.

No. 18,405.

Patented Oct. 13, 1857.

UNITED STATES PATENT OFFICE.

N. A. PATTERSON, OF KINGSTON, TENNESSEE.

IMPROVEMENT IN HARVESTERS.

Specification forming part of Letters Patent No. 18,405, dated October 13, 1857.

To all whom it may concern:

Be it known that I, N. A. PATTERSON, of Kingston, in the county of Roane and State of Tennessee, have invented a new and useful Improvement in Grain and Grass Harvesters; and I do hereby declare that the following is a full, clear, and exact description of the same, reference being had to the annexed drawings, making a part of this specification, in which—

Figure 1 is a longitudinal vertical section of my improvement, taken in the line xx , Fig. 2. Fig. 2 is a plan or top view of the same. Fig. 3 is a detached view of the device by which the double-tree is operated.

Similar letters of reference indicate corresponding parts in the several figures.

This invention relates to a novel means employed for guiding and turning the machine; and it consists in connecting the front or movable axle with the double-tree in such a way that as said axle is turned the double-tree will be simultaneously moved or shifted and the axle and double-tree have a proper relative position with each other, so that the power of the team will be applied in the most direct or advantageous manner to the machine as the same is guided or turned.

The invention is applicable to that old and original class of machines in which the team is attached back of the cutting device, so as to avoid side draft and also the trampling down of the standing grass or grain, and is designed to obviate the objection attending such machines, and which has hitherto prevented them being generally used—viz., the difficulty in guiding or turning the same and the general unwieldiness of the whole, owing to the manner in which the power was applied.

To enable those skilled in the art to fully understand and construct my invention, I will proceed to describe it.

A represents the frame of the machine.

B is the front and C is the back axle. The back axle is permanently attached to the frame A; but the front axle turns on a bolt, a, as is usual with all four-wheeled vehicles.

To the back side of the front axle, B, and at its center, a horizontal bar or arm, D, is attached, and to the end of this arm there is attached a segment-rack, E.

F is the reach which connects the bolster G with the back axle, C. To the under side

of the reach there is attached a curved or segment block, b, which fits in a corresponding-shaped recess in the bar or arm D, and serves as guide for the same.

G is a shaft, which is placed longitudinally on the frame A, the front end of said shaft having its bearings c attached to the reach, and the back end having its bearing in the upper end of an upright, d, attached to the back axle, C.

To the back end of the shaft G a hand-wheel, H, is attached, said wheel being directly in front of the driver's seat I, which seat is placed on a platform, J, attached to the back axle, C.

On the front end of the shaft G a pinion, K, is placed, and this pinion gears into the rack E. It will consequently be seen that by turning the shaft G the front axle, B, may be turned so as to guide the machine either to the right or left.

L is the double-tree, to which the team is attached. The double-tree is attached by a link, e, with a sliding bar, M, which is fitted between a bar, N, attached to the reach F and the back axle, C. This bar has the two ends of a rope or chain, O, attached to it at opposite ends, said rope or chain passing around the shaft G and making several turns thereon.

From the above description of parts it will be seen that by turning the shaft G the axle B will not only be turned but the double-tree L will also be moved or shifted. For instance, if the shaft G be turned from left to right, as indicated by the red arrow, the axle B will be moved or turned as indicated in red, and the double-tree L will be moved to the left, as also indicated in red; and if the shaft G be turned in a reverse direction, the axle and double-tree will be moved in reverse directions. Consequently, whenever the machine is to be turned the team is moved toward the wheels having the greater circuit to pass over, and the power or draft is therefore applied where it is most needed—viz., near said wheels—so as to act in the most direct manner in turning the machine. Were the double-tree a permanent fixture, as is usual, the team would not directly aid in turning the machine; but the machine, unless the team be guided by the driver, would bear or act upon the team, they being merely passive so far as the turning of the machine is concerned. It will there-

fore be seen that in all cases when a team is applied to harvesters behind the cutting device my improvement possesses a very appreciable advantage.

Having thus described my invention, what I claim as new, and desire to secure by Letters Patent, is—

Connecting the axle B with the double-tree L, substantially as and for the purpose set forth.
